UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIES.

1,147,994.

Specification of Letters Patent. Patented July 27, 1915.

Application filed April 6, 1914. Serial No. 829,750.

To all whom it may concern:

Be it known that I, RICHARD LESTER WILCOX, a citizen of the United States, residing at Waterbury, in the county of New Haven and State of Connecticut, have invented certain new and useful Improvements in Dies, of which the following is a specification, reference being had therein to the accompanying drawings.

10 My invention relates to new and useful improvements in dies, referring more particularly to dies for heading or like machines.

15 It is the object of my invention, among other things, to construct dies of this character that will be serviceable for a much longer period than the dies heretofore made, constructed of materially less metal, and at a lower cost.

20 To these, and other ends, my invention consists in the dies constructed and operating substantially as described, and more particularly pointed out in the claims.

25 Referring to the drawings, in which like numerals of reference designate like parts in the several figures; Figure 1 is a perspective view of one set of dies; Fig. 2 is a fragmentary view of a set of the dies with some of the parts immediately adjacent thereto, 30 as they are mounted in a heading machine; and Fig. 3 is a transverse sectional view of the parts shown in Fig. 2 taken upon line A—B of said figure.

35 It is the practice to construct the dies to be used in heading machines substantially square in cross section, with a semi-circular groove in each side thereof of substantially the same width as the diameter of the wire rod and of a depth equal to the radius thereof, with one end formed to correspond in shape with the head of the finished bolt or screw.

40 These dies have been mounted in pairs so that the grooves in the sides of each of the dies unite to form an opening the entire length of the die with a recess at one end for the head, in its entirety, the groove and recess being the same shape as the finished blank.

45 50 In the process of heading blanks, the wire is fed between the dies the required distance, that is, with one end thereof projecting beyond the end of the dies, which are then brought together so that the opposite faces

thereof contact with each other. When so united they are moved laterally and the rear end of the die cuts the wire within the dies from the rod length, and subsequently the punches upset that portion of the projecting wire to form a head thereon of substantially the same shape as the recess in the end of the die. By this practice the ends of the dies do all of the work, the rear end cutting and the front end notwithstanding the shock required to displace or upset the wire rod to form the head. As the dies wear they are thrown away and new ones substituted. The dies most frequently wear out and break at that end where the head is formed, and are therefore discarded, while the so-called cutting end is in perfect condition. These, and other objections, I have overcome by making the dies of interchangeable sections that are severally designated in the drawings by the reference numerals 1 and 2, the former being the head section and considerably shorter than the latter or cutting section. One end of the head section is provided with recesses 3 at the end of the grooves 4 to form the blank head. Sections 1, being those that more frequently break and wear out, are comparatively short in length, and therefore require much less stock than a die of the combined length of both sections, and are necessarily produced at a very much lower labor cost, and can be discarded and a new section substituted without casting aside the entire die, and again, the sections 1 can be utilized in the manufacture of blanks of various lengths by substituting new sections 2 of different lengths, a practice not heretofore possible, a die being required for each length of blank. The sections 2 can also be turned end for end so that eight cutting off surfaces are provided instead of four, as at present, thereby doubling the life of this portion of the die.

45 50 The dies are usually mounted in a die block 6 and movable therebetween. This die block is secured in the bed of a header, designated in the drawing by the numeral 6. A hardened backing block 7 is usually inserted in the bed to take the strain of the heading operation off the bed.

55 On either side of the dies, and between the die block 5 and cover 18, are the filler plates 8 and 9. Contacting with the filler plate 8 is a yielding plate 10, mounted within a

recess 11 in the bed 6, and moved in one direction by one or more springs 12.

Engaging the filler block 9 is a pusher block 13, against which abut the ends of the plungers 14. During the feeding operation the dies are in the position shown by full lines in Fig. 2, the recesses 4 in the meeting faces of the dies being opposite the opening 15, through which the wire is fed. At 10 the termination of the feeding operation the dies are moved laterally through the action of the plungers 14, by means not herein shown, and shifted to a position wherein the axes of said recesses 4 are coincident with the broken line 16 (Fig. 2). During this lateral shifting of the dies the wire is cut off between the rear end of the sections 2 and the cutter block 17.

The heading operation takes place when 20 the recesses are coincident with the line 16, at which time the wire abuts against the face of the cutter 17. The dies are returned to their original position to have the blank ejected and receive another wire length by 25 the withdrawal of the plungers 14 and the action of the springs 12.

While I have illustrated and described the general method of mounting and operating these dies in a heading machine, I do 30 not desire to be understood as limiting the use of my dies to such mechanism, or in the manner described, the invention relating to the dies alone, and not to any surrounding mechanism with which they may be associated, or the method of their use.

Having described my invention, what I claim as new and desire to secure by Letters Patent, is:—

1. Dies for a header or similar use, constructed of two separate sections placed together with the end of one section against the other section so as to form a single die, each of said sections having grooves in the sides thereof that form an extension of the 45 grooves in the other section, one of said sections having a recess in one end thereof for forming the head of the blank and extending only part way through the section, which is of sufficient thickness and size to withstand the shock, pressure and pounding of the punches against it without crystallizing.

2. Dies for a header or similar use, having a groove in one face thereof, constructed of a heading section and a cutting off sec-

tion and placed in such relation to each other that the end of one section is against the end of the other section with the groove of one section forming an extension of the groove in the other section, the latter section being relatively longer than the former 60 and the groove in the former section opening into a heading recess that extends only partly through said section..

3. Dies for a header or similar use, having a groove in one face thereof, constructed of 65 a heading section and a cutting off section, the latter being relatively longer than the former and capable of being reversed end for end, said sections being placed in such relation to each other that the end of one 70 section is against the end of the other section with the groove of one section forming an extension of the groove of the other section, said cutting off section having a heading recess in its outer end that extends only 75 part way through the section.

4. Dies for a header or similar use, constructed of a heading section and a cutting off section, substantially rectangular in cross section with a groove in each side thereof 80 parallel to its length, the grooves in the heading section terminating in an enlarged head recess, these sections being placed in such relation to each other that the end of one section is against the end of the other section 85 with the groove in the side of one section forming a continuation of the groove in the side of the other section.

5. Dies for a header or similar use, constructed of two sections, each being of substantially the same shape and size in cross section, one of said sections having a heading recess in one end thereof, and both sections being so placed in relation to each other, that one section is substantially an 95 extension of the other section, and combined are substantially the same length as the blank, headed therein, with the head of said blank formed at the outer end of one section and the blank cut off from the wire 100 length by the opposite end of the other section.

In testimony whereof I affix my signature in presence of two witnesses:

RICHARD LESTER WILCOX.
